UNITED STATES PATENT OFFICE

EDMUND C. MORGAN, OF CHICAGO, ILLINOIS.

PICK MINING-MACHINE.

No. 902,756.

Specification of Letters Patent.

Patented Nov. 3, 1908.

Application filed December 10, 1903. Serial No. 184,597.

To all whom it may concern:

Be it known that I, EDMUND C. MORGAN, a citizen of the United States, residing at Chicago, in the county of Cook and State 5 of Illinois, have invented a new and useful Pick Mining-Machine, of which the following is a specification.

This invention relates to pick mining machines.

10 The object of the invention is to provide means for receiving the recoil due to the impact of the pick or other tool.

A further object of the invention is to provide means for relieving the operator of 15 shock or jar due to the impact of the pick or other tool.

A further object of the invention is to provide means automatically operated at the instant of impact of the pick or other tool, 20 whereby the supporting frame is held against recoil or undue shock or jar.

Other objects of the invention will appear more fully hereinafter.

The invention consists substantially in the 25 construction, combination, location and arrangement of parts, all as will be more fully hereinafter set forth, as shown in the accompanying drawings, and finally pointed out in the appended claims.

30 Referring to the accompanying drawings, and to the various views and reference signs appearing thereon,—Figure 1 is a view in top plan, somewhat diagrammatic, showing a pick mining machine and the application 35 thereto of a recoil locking mechanism embraced within the spirit and scope of my invention. Fig. 2 is a side elevation. Fig. 3 is a broken detail view in top plan, somewhat diagrammatic, showing a modified form of 40 automatic locking mechanism embodying the principles of my invention. Fig. 4 is a similar view, parts in section, of another modified form of mechanism embraced within the spirit and scope of my invention.

45 The same part is designated by the same reference sign wherever it occurs throughout the several views.

In the operation of pick mining machinery it is usually customary to mount the 50 pick or other tool upon a frame or truck having wheels, by which the frame may be suitably moved into proper position for the pick or other tool to perform its work, the frame being provided with a hand-grip, 55 which is grasped by the attendant in properly positioning the tool for its work. The

impact of the pick or other tool against the wall or vein of coal or the like imparts a recoil shock or jar to the entire frame and through the handle or grip which is grasped 60 by the attendant to the arms of the attendant. In order to relieve this shock or jar upon the attendant as much as possible, and also in order to relieve the attendant as much as possible of the work or labor required to 65 properly position and present the pick or other tool with reference to its work, it has been a common practice to mount the frame of the machine upon boards or stringers, which have been tilted at one end so as to be 70 inclined towards the point where the blow of the tool is to be delivered, thereby enabling gravity to operate upon the carriage or frame of the machine in a direction tending to carry the same towards the point of application of the pick or other tool to its 75 work. This expedient, however, has not been sufficient to relieve the attendant of injurious shock and jar due to the impact or blow of the pick or tool and the recoil resulting therefrom.

It is among the special purposes of my present invention to provide means for automatically locking the frame carrying the pick or tool and its actuating mechanism at 85 the instant the blow or impact of the pick or tool is delivered, and to automatically release such locking mechanism upon the withdrawal movement of the pick or tool, so as to leave the same free to be shifted or moved 90 by the attendant as occasion may require.

In the accompanying drawings I have merely indicated in outline and in dotted lines the construction of the pick or tool, its actuating mechanism and supporting frame- 95 work or truck, and have shown in full lines the features of improvement embraced within the spirit and scope of my invention.

Referring to the accompanying drawings, reference sign A designates generally the 100 supporting frame of the carriage, which is provided with the gudgeons B, carrying rollers C, upon which the frame is supported. The frame A comprises the usual cylinder D, in which operates a piston E, to 105 which is connected the pick or other tool F, a pressure medium being admitted to the cylinder for reciprocating the pick or other tool, or the rod G carrying the same, in order to enable the pick or other tool to perform its desired objects. These parts may be of the usual or any well known construc- 110

tion and arrangement, and in the specific details thereof form no part of my present invention. The carriage in the operation of the machine and as above indicated, is mounted upon the stringers, timbers, boards or the like, H, the latter being anchored to the ground in any convenient manner, as, for instance, by means of an anchor bar J, or otherwise.

10 In carrying out the principles of my invention I propose to provide means automatically operated at or immediately before the delivery of the blow or impact of the pick or tool to lock or anchor the carriage or frame carrying the pick or tool and its actuating mechanism to the ground and against recoil, and to automatically release such locking means upon the reverse movement of the pick or tool. This idea may be embodied in a wide variety of specific constructions and arrangements and still fall within the spirit and scope of my invention. While, therefore, I have shown and will now describe various constructions and arrangements for accomplishing the desired object, 15 I do not desire to be limited or restricted thereto.

In carrying out my invention I loosely sleeve or mount upon each of the gudgeons 30 B a drum or pulley K, to which is secured and around which is wrapped one end of a cable or flexible connection L, the other end of said cable or connection being led forwardly or towards the point of application 35 of the tool to its work, and each of the drums or pulleys K is provided with teeth or other suitable abutments N on the side or face thereof, or otherwise, as may be convenient. The other end of the cable or other connection 40 L is hooked or otherwise secured, as at M, to one of the beams or stringers constituting the platform or support therefor, thereby giving the carriage a ground anchorage. Suitably connected to each of the 45 drums or pulleys K is one end of a spring O, the other end of each of said springs being connected to its associated stub or gudgeon B, the tension of said springs being normally exerted in a direction to maintain 50 the cable or other connection L taut.

In order to lock the machine and its supporting frame against recoil under the influence of the impact or blow delivered by the pick or tool and at or about the instant 55 such blow or impact is delivered, I pivotally mount upon the frame adjacent to each drum or pulley K, a pivoted lever P, each having its end arranged to be rocked into engagement with or between the teeth or lugs N on its associated drum or pulley K. Each lever P is normally held out of engaging relation with respect to the teeth or lugs N on its associated drum or pulley in any convenient manner, as, for instance, by 60 means of a spring Q. Associated with each

lever P is a cylinder R, in which operates a piston S, said piston being suitably connected to the other end of lever P.

From the foregoing description it will be seen that when a pressure medium is admitted to the cylinders R, the pistons S therein are moved, thereby rocking levers P in a direction to carry the free ends thereof into engaging relation with respect to the teeth or lugs N on their associated drums or pulleys K. The pressure medium may be of any desired or suitable arrangement, and may be controlled in any suitable manner. It is desirable, however, to so control such pressure medium as to admit the same to the cylinders R at or immediately before the delivery of the blow or impact of the pick or other tool, so that at the moment the pick or other tool delivers its blow the drums or pulleys K are locked against rotation, and hence the recoil of the impact or blow will be taken upon the cables or other connections L, instead of being transmitted through the frame of the machine to the attendant. The admission of the pressure medium to cylinders R should also be controlled automatically so as to retain the locking engagement of levers P and the drums or pulleys K during the time the blow of the tool or pick is being delivered, and also so as to be automatically released upon the return movement of the pick or tool. In Fig. 1 I have shown one arrangement for accomplishing this object, wherein a pipe A' communicates with a suitable source of pressure medium, and a pipe B' with the exhaust. These pipes deliver into a valve C', normally but yieldingly held in a centered position by spring D' to cut off both the supply and exhaust pipes A' B' from a pipe E'. The springs 95 D' are arranged on opposite sides of a handle or projection F' connected to the valve, said handle or projection arranged, when held in centered or normal position, to extend into the path of a lug G', connected 100 to move or reciprocate with the stem or rod G carrying the pick or other tool F, and the arrangement of the valve is such that when the pick or other tool moves in a direction 105 to deliver its blow or impact the lug G' engages the projection or handle F' of valve C', thereby rocking said valve in a direction 110 to open communication between supply pipe A' and the service pipe E'. 115

The parts are intended to be so relatively positioned that the opening of the supply pipe A' and service pipe E' to communication with each other is effected at or just before the instant of impact or blow of the pick or tool. As the pick or tool continues its movement in a direction to deliver its blow the lug G' passes or wipes by valve handle F', thereby permitting said handle to be automatically returned or restored to its normal or centered position, thereby cutting 120

off supply of the pressure medium to the service pipe E'. On the return movement of the pick or other tool the lug G' engages the valve handle F' from the opposite direction, thereby rocking said valve in a direction to open communication between the service pipe E' and exhaust pipe B', and hence permitting the pressure medium which has entered the service pipe E' and the devices presently to be referred to, which are in communication with said service pipe to escape to exhaust. Upon the opening of communication between pressure supply pipe A' and service pipe E' the pressure medium is admitted to each of the cylinders R through the service pipe E', which is arranged to communicate with each of said cylinders, as clearly illustrated. Thus, it will be seen that or just before the instant of impact or delivery of the blow of the pick or other tool pressure medium is admitted to the cylinders R, thereby moving the pistons therein and rocking locking levers P into engaging relation with respect to their associated drums or pulleys K, and hence locking the machine against recoil movement. The pressure medium thus admitted to the cylinders R is maintained so as to maintain the locking connection of levers P and drums or pulleys K until the return movement of the pick or other tool, when the service pipe E' is again temporarily opened to exhaust. Thus, it will be seen that I provide a mechanism which is automatically locked and released, whereby the shock or jar due to recoil from the delivery of the impact or blow of the pick or other tool is taken up by the cables or other connections L, thereby relieving the operator or attendant.

If desired, and in order to still further insure a locking of the frame against recoil movement, I may employ a brake or shoe H', for each of the truck wheels C, each brake or shoe being connected to a piston J', operating in the cylinder K', which cylinders are also in communication with service pipe E', as clearly shown.

If desired, I may employ a hand-controlled valve L' in the communication between service pipe E' and the cylinders R and K', so that either one or the other of these lockings or braking devices may cut out of operation by hand, if necessary or desirable.

In the operation of an apparatus of the class above referred to it is desirable to vary or regulate the vertical inclination of the pick or other tool with reference to the point of delivery of its impact or blow. This may be accomplished by means of a rod carried by the machine and adjustable relatively thereto and arranged to bear upon the floor of the platform, or upon the planking or other support of the machine frame. To this end I propose to employ an adjusting rod

M', having, if desired, serrated teeth on one side thereof with which cooperates a similarly serrated plunger or piston N', mounted or carried in a cylinder O', which is arranged in communication with service pipe E', so that at the instant pressure medium is admitted to the locking and braking cylinders it may also be admitted to the cylinder O', thereby causing plunger N' to clamp tight up against the adjusting rod M', and hence holding said adjusting rod against displacement through shock or jar due to the delivery of the impact or blow of the pick or other tool.

Instead of controlling the supply of operating medium to the locking and brake cylinders through an independent valve, which is actuated automatically by a lug on the rod or stem carrying the pick or other tool, it is obvious that the supply and exhaust of pressure medium may be controlled in many other ways. For instance, I have shown an arrangement in Fig. 4, wherein the supply of pressure medium to the locking and brake cylinders or to the service pipe E' may be controlled by the valve A², which controls the supply and exhaust of pressure medium to the cylinder for operating the pick or other tool. It is obvious that the locking of the frame against recoil due to the force of the impact or blow delivered by the pick or other tool, may be effected mechanically instead of by a pressure medium and still accomplish the desired objects. In Fig. 3 I have indicated an arrangement by which this result may be accomplished, wherein the locking lever P² instead of being actuated pneumatically, as above described, may be operated by a pivoted lever B², having a spring arm C² arranged to engage one arm of lever P², the other arm of said lever B² being arranged in the path of a lug G² on the piston rod G, so that as the pick or other tool, or the rod G upon which said tool is supported, advances to deliver its blow the arm of lever B² is engaged by lug G², thereby rocking said lever in a direction for the spring arm C² thereof to engage one arm of lever P², the other arm of said lever being arranged to interlock with the teeth or lugs N on drum K.

It is obvious that many modifications, changes or variations might be devised for accomplishing the desired objects, but all embodying the principles of my invention. I do not desire, therefore, to be limited or restricted to the exact details of construction and arrangement shown and above described.

In the use of an automatically releasable locking mechanism such as above described I am enabled to operate the pick or other tool with less injury or jar to the operator than heretofore, and I am also enabled to operate the machine on a less incline of the supporting tracks or planking H, and in fact

such supporting planks or the tilt thereof in a direction toward the point of application of the impact or blow may be entirely dispensed with, if desired, inasmuch as recoil is provided against in accordance with the principles of my invention, which is a decided advantage, as thereby the operator is enabled more easily and readily to shift the position of the machine in order to properly 10 present the pick or other tool to its work.

In order to permit the lateral swinging movement of the machine frame without twisting the cables or other connection L off of drums K, said cables may be arranged to 15 operate over pivoted guides K², (see Fig. 2) the function of which is to prevent the cable from being twisted or rendered off of their drums K.

While I have described my invention as 20 applied to a pick mining machine, it is obvious that the principles thereof are equally applicable to other kinds of machines employing a reciprocating part, and wherever it may be desirable to lock the machine against recoil, shock or jar due to the operation 25 of the reciprocating part.

It is obvious the releasing of the locking means may be effected otherwise than automatically without departure from the 30 spirit and scope of my invention, and, if desired, the construction may be such as to permit the pick or other tool to remain in its advanced position and without any release of the locking means.

From the foregoing description it will be observed that I provide an exceedingly simple means for locking the machine against recoil or against shock or jar due to the impact or blow delivered by the tool, and consequently I am enabled to greatly reduce the 40 size and weight of the supporting framework or of the castings forming the same. This is an exceedingly desirable result, for the reason that thereby not only is the expense or cost of manufacture reduced, but also the machine is thereby made much lighter, and hence an attendant may more easily and readily handle the same in the 45 performance of its work.

Having now set forth the object and nature of my invention and various constructions embodying the principles thereof, and having described such constructions, their purposes, function and mode of operation, what I claim as new and useful and of my 55 own invention, and desire to secure by Letters Patent, is:

1. In a mining machine, a tool, and means for operating the same, in combination with 60 a positive lock for holding the machine against recoil, and positively acting means controlled by the tool for actuating said lock.

2. In a mining machine, the combination 65 with a carriage, a tool, and means for oper-

ating the tool, of means co-operatively related to the tool for locking the carriage against recoil, comprising a ground anchoring means, and positive means for fixing the carriage and ground anchoring means 70 against relative movement.

3. In a mining machine, the combination with a carriage, a tool and means for operating the tool, of means for locking the carriage against recoil, comprising ground anchoring means, means for fixing the carriage and ground anchoring means against relative retrograde movement, and means co-operatively related to the tool for actuating the last said means. 75

4. In a mining machine, the combination with a carriage, a tool and means for operating the tool, of a ground anchoring means for the carriage, comprising a flexible connection, a take-up for the flexible connection, means operating in concert with the movement of the carriage for actuating said take-up automatically to take up the slack therein as the carriage advances, and means for positively locking the carriage against 80 retrograde movement. 85

5. In a mining machine, the combination with a carriage, a tool and means for operating the tool, of means for locking the carriage against recoil, comprising rigid abutments, and a latch or stop for engagement with said abutments, and means operating in concert with the movement of the tool for actuating said latch or stop. 95

6. In a mining machine, the combination 100 with a carriage, a tool and means for operating the tool, of a positive locking means for holding the carriage against recoil movement, and positive means controlled by the movement of the tool for causing the engagement of said locking means at predetermined intervals. 105

7. In a mining machine, the combination 110 with a carriage, a tool and means for operating the tool, of a positive lock for locking the carriage against recoil movement, and positively acting means co-operatively related to the tool for causing the lock to alternately engage and disengage. 115

8. In a mining machine, the combination 115 with a carriage, a tool and means for operating the tool, of pressure actuated means for locking the carriage against recoil, comprising a ground anchoring means, positive means for fixing the carriage and ground anchoring means against relative movement, and means co-operatively related to the tool for actuating said pressure actuated locking means. 120

9. In a mining machine, the combination 125 with a carriage, a tool and means for operating the tool, of means for locking the tool against recoil movement, comprising a latch, and rigid positive abutments with which the latch engages, and means operated coinci- 130

dently with the withdrawal movement of the tool for releasing said latch.

10. In a pick mining or similar machine, and in combination with a frame, a reciprocating tool mounted therein, and means for actuating said tool, of a drum mounted upon said frame, means for yieldingly maintaining said drum in one limit of rotary movement, an anchoring cable having one end 10 coiled upon said drum and secured thereto, the other end of said cable being led towards the point of delivery of the blow of the tool and suitably anchored, a locking mechanism for locking said drum against 15 rotary movement, and means actuated coincidentally with the advancement of the tool to its work for operating said locking mechanism, as and for the purpose set forth.

11. In a pick mining or similar machine, 20 and in combination with a frame having gudgeons, and a tool mounted to reciprocate upon said frame and means for actuating the same, of drums mounted upon said gudgeons to freely rotate thereon, an anchoring 25 cable for each drum, one end of said cable being wound upon and secured to its associated drum, the other end of said cable leading toward the point of delivery of the blow of the tool and suitably anchored, a 30 locking device for each drum, and means operated coincidentally with the advancement of the tool to its work for actuating said locking mechanism, as and for the purpose set forth.

35. 12. In a pick mining or other machine, a frame carrying a reciprocating tool, and means for operating said tool, of a locking device for said frame including a pressure cylinder and a piston operating therein, a 40 service pipe communicating with said cylinder, a controlling valve for said service pipe having a handle or projection, and a stud connected to move with said tool and arranged to engage said handle or projection 45 to actuate said valve, as and for the purpose set forth.

13. In a pick mining or similar machine, and in combination with a frame and a reciprocating tool mounted therein, and means 50 for actuating said tool, of a locking device for said frame to prevent recoil due to the impact or blow delivered by the tool and including a cylinder and piston, a pressure medium service pipe communicating with 55 said cylinder, a valve controlling the supply and exhaust of pressure medium to said service pipe, said valve having a projecting handle, means for normally maintaining said valve in position to cut off supply or exhaust from said service pipe, and a lug or finger connected to reciprocate with said tool and co-operating with said handle to actuate said valve, as and for the purpose set forth.

65. 14. In a pick mining or similar machine,

and in combination with a frame and a reciprocating tool, of a locking device for said frame to lock the same against recoil under the influence of the blow delivered by said tool and including a cylinder and piston, a 70 service pipe communicating with said cylinder, pressure medium supply and exhaust pipes, a valve controlling the communication between said supply and exhaust pipes and said service pipe, said valve operating, 75 when actuated in one direction, to admit pressure medium to said service pipe, and when actuated in the opposite direction to exhaust the pressure medium from said exhaust pipe, means normally operating to 80 maintain said valve in position to cut off communication between said service pipe and said supply and exhaust pipes, and means connected to move with said tool for shifting said valve; as and for the purpose 85 set forth.

15. In a pick mining or similar machine, a frame carrying a reciprocating tool, a locking device for preventing recoil of said frame due to the impact of the blow delivered by the tool, and including a drum having teeth or lugs, means whereby the drums are caused to rotate, a lever co-operating with said lugs to lock said drum against rotary movement, means for normally maintaining said lever out of engaging relation with respect to said lugs, a cylinder and piston, said piston connected to actuate said lever into locking relation 95 with respect to said lugs, a service pipe delivering to said cylinder, a valve for controlling the supply and exhaust of pressure medium to said service pipe, means actuated coincidentally with the movement of said tool for actuating said valve, and a cable coiled 100 upon said drum and having the free end thereof suitably anchored, as and for the purpose set forth.

16. In a pick mining or similar machine, a framework carrying a reciprocating tool, a locking mechanism for said frame for locking the same against recoil due to the impact of the blow delivered by the tool, and including an anchoring device having yielding connection with said frame, and means for automatically locking said yielding connection to the frame, said means operating coincidentally with the advancement of the tool to its work to deliver its blow, as and for the purpose set forth.

17. In a pick mining or similar machine employing a reciprocating tool, a frame upon which said tool is mounted, supporting wheels for said frame, a locking mechanism for locking said frame against recoil due to the impact or blow delivered by said tool, and including a cylinder and piston, a locking device connected to said piston and arranged, when actuated, to positively 125 lock the frame against recoil, a brake for 130

said supporting wheels including a cylinder and piston, a pressure medium service pipe communication with both of said cylinders, and an automatically operated valve 5 for controlling the supply and exhaust of pressure medium to said service pipe, as and for the purpose set forth.

18. In a pick mining or similar machine, a frame, a reciprocatory tool mounted thereon, and means for adjusting the vertical inclination of said tool, including an adjusting rod, a cylinder, a clamp piston operating in said cylinder and arranged to engage said rod, a pressure medium service pipe communication with said cylinder, and means 15 for controlling the supply and exhaust of pressure medium to said pipe, as and for the purpose set forth.

19. In a pick mining or similar machine, 20 a frame, a reciprocatory tool mounted thereon, supporting wheels for said frame, locking mechanism for locking said frame against recoil due to the blow or impact delivered by said tool, and including a cylinder and piston, a brake for said supporting wheels, including a cylinder and piston, a service pipe delivering to said cylinders, a valve arranged in said service pipe and mainly operating for cutting off either one 25 or the other of said cylinders from communication with said pipe, and means for automatically opening and closing communication between said service pipe and the source of supply and exhaust for the pressure medium, as and for the purpose set forth.

20. In a pick mining or similar machine, a supporting frame carrying a reciprocatory

tool, said frame provided with gudgeons carrying supporting wheels, drums loosely 40 sleeved upon said gudgeons, a cable having one end wound upon each of said drums and connected thereto, the other end of said cable leading towards the point of delivery of a blow of said tool and suitably anchored, 45 a spring connected to each of said drums for yieldingly maintaining the same in one limit of rotary movement upon said gudgeons to maintain said cables taut, and an automatically operated locking mechanism 50 for said drums, as and for the purpose set forth.

21. In a pick mining or similar machine, and in combination with a reciprocatory tool, of means for adjusting the vertical inclination of such tool, and means for automatically clamping such adjusting means at the instant of delivery of the blow of the tool, as and for the purpose set forth.

22. In a mining machine, the combination 60 of a carriage, a tool, means for operating the tool, means for locking the tool against recoil movement comprising a latch, rigid positive abutments with which the latch engages, and means operated coincidently 65 operatively related to the carriage and with the withdrawal movement of the tool for releasing the latch.

In witness whereof, I have hereunto set my hand this 8th day of December 1903, 70 in the presence of the subscribing witnesses.

EDMUND C. MORGAN.
